US0D1003847S

(12) **United States Design Patent** (10) **Patent No.:** **US D1,003,847 S**
(45) **Date of Patent:** ** Nov. 7, 2023

(54) **MOBILE PHONE**

(71) Applicant: **HUAWEI TECHNOLOGIES CO., LTD.**, Shenzhen (CN)

(72) Inventors: **Ting Xu**, Shanghai (CN); **Lijun Qi**, Shanghai (CN); **Jiaxyi Wang**, Shanghai (CN); **Jue Yuan**, Shanghai (CN); **Haosen Xu**, Shanghai (CN)

(73) Assignee: **HUAWEI TECHNOLOGIES CO., LTD.**, Shenzhen (CN)

(**) Term: **15 Years**

(21) Appl. No.: **29/726,998**

(22) Filed: **Mar. 6, 2020**

(30) **Foreign Application Priority Data**

Sep. 6, 2019 (CN) 201930492265.1

(51) **LOC (14) Cl.** **14-03**

(52) **U.S. Cl.** ..... **D14/138 G**
USPC ..
